[57] CLAIM

The ornamental design for a slotted intramedullary rod, substantially as shown and described.

DESCRIPTION

FIG. 1 is a side view of a slotted intramedullary rod showing my new design;

FIG. 2 is a top view thereof;

FIG. 3 is a lefthand end view thereof;

FIG. 4 is a righthand end view thereof; and

FIG. 5 is a sectional view taken along the line 5—5 of the slotted intramedullary rod shown in FIG. 1.
